Attorneys,

UNITED STATES PATENT OFFICE.

JOHN REUTHER, OF HAMBURG, NEW YORK.

DESIGN FOR A BABY-JUMPER.

58,163.

Specification for Design. Patented June 14, 1921.

Application filed March 18, 1921. Serial No. 453,400. Term of patent 14 years.

To all whom it may concern:

Be it known that I, JOHN REUTHER, a citizen of the United States, residing at Hamburg, in the county of Erie and State of New York, have invented a new, original, and ornamental Design for a Baby-Jumper, of which the following is a specification, reference being had to the accompanying drawing, forming part thereof.

The figure is a perspective view of the baby jumper showing my new design.

I claim:

The ornamental design for a baby jumper, as shown.

JOHN REUTHER.
